UNITED STATES PATENT OFFICE.

LOUIS O. FORMAN, OF SOUTH ORANGE, NEW JERSEY, ASSIGNOR TO GILLIS & GEOGHEGAN, OF NEW YORK, N. Y., A FIRM.

HOISTING APPARATUS.

1,024,885.

Specification of Letters Patent. Patented Apr. 30, 1912.

Application filed April 8, 1911. Serial No. 619,697.

To all whom it may concern:

Be it known that I, LOUIS O. FORMAN, a citizen of the United States, residing at South Orange, in the county of Essex and State of New Jersey, have invented a certain new and useful Improvement in Hoisting Apparatus, of which the following is a specification.

The invention relates more particularly to apparatus for elevating ashes from cellar to street and analogous light hoisting work, and the object of the invention is to provide a simple, cheap, easily operated mechanism for such purpose, capable of being collapsed telescopically when not in use, and which may be easily installed with but little alteration in adapting it for service in various situations.

The invention consists in certain novel features of construction and arrangement by which the above objects are attained, to be hereinafter described and pointed out in the claims.

The accompanying drawings form a part of this specification and show the invention as it has been carried out in practice.

Figure 1 is a side elevation showing the hoist with its standard extended above the street level, the sidewalk being shown in section. The remaining figures are on a larger scale. Fig. 2 is a plan view of the hoisting mechanism at the upper end of the standard. Fig. 3 is a corresponding section of a portion of the same, showing the brake. Fig. 4 is a vertical section, partly in elevation, showing the means employed in mounting the hoisting mechanism upon the standard. Fig. 5 is a plan view, partly in horizontal section, showing the elevating mechanism for raising or lowering the standard and hoisting mechanism thereon. Fig. 6 is a vertical section through portions of the post and standard, showing the lower end of the elevating rack in elevation. Fig. 7 is a corresponding front view, partly in vertical section.

Similar letters of reference indicate the same parts in all the figures.

A is a hollow post firmly fixed by means of the foot A¹ upon the floor or cellar bottom beneath an opening m in the sidewalk M, which is closed when the hoist is not in use, by a cover M¹ indicated by dotted lines

in Fig. 1. Braces A² from the post to adjacent side walls, not shown, aid in supporting the post.

Within the vertical post is a tubular standard B fitted to slide telescopically and inclosing a core B¹ on which is a rack B² with its teeth exposed along a slot b in the standard and presented at a slot a in the post for engagement by a toothed rack-wheel C¹ mounted on a transverse shaft C supported in a yoke D made in halves and arranged to grasp the cylindrical surface of the post. The yoke is thus firmly clamped in position near the base of the post by bolts D¹ and D², the latter having a tubular distance-strut D³ serving to hold the arms D⁴ of the yoke properly separated. On the overhung end of the shaft C is a spur-gear wheel C² in mesh with a pinion C³ on a shaft C⁴ mounted in bosses D⁵ on the yoke. The end of the shaft C⁴ opposite to the pinion is extended and squared to receive a crank L by which the shaft may be turned and the standard raised or lowered through the above described train of gearing. A pawl D⁶ on the yoke, when thrown into engagement with the rack-wheel C¹ serves to prevent the descent of the standard until released, and a pin A³ thrust through oppositely placed holes a¹ in the post supports the standard against accidental descent when completely elevated. The pin is preferably secured to the post by a light chain.

On the upper end of the standard is screwed a coupling B³ which receives a threaded sleeve B⁴ inclosing a downwardly projecting leg of a frame F, having parallel horizontally extending overhung arms F² F² in which the hoisting gear is supported. The leg F¹ is secured against vertical movement in the sleeve by a plate F³ abutting against the lower end of the sleeve within the coupling and fastened by an axially arranged screw F⁴ extending into the lower end of the leg, and is held against rotation by a set-screw F⁵ engaged in one of the several vertical grooves f provided for the purpose.

G is a shaft mounted in bearings in the arms F² F² and carrying a pinion G¹ in mesh with a gear-wheel H¹ on a shaft H parallel with the shaft G and mounted at the extremities of the overhanging arms. On the projecting end of the shaft G is a

squared portion G^2 receiving a crank which may be the same crank L above mentioned, or a similar crank L^1 as shown.

5 Adjacent to the gear-wheel H^1 and located centrally between the arms F^2 is a winding-spool H^2 on which the hoisting cable J is wound, preferably a light wire rope provided with a hook J^1 adapted to engage the bail of an ash-can K or other load to be 10 lifted. A pawl F^6 on the frame is arranged to engage the teeth of the pinion G^1 and thus hold the load, and in order to permit the latter to be lowered gently when the pinion is released, a brake-drum G^3 is 15 mounted on the shaft G , partially encircled by a strap or brake-band N attached at one end to the frame F and at the other to a flat bar N^1 , otherwise not connected to the frame, but bent as shown in Fig. 3 to rest 20 upon the upper surface of the frame and act as a lever in tightening the band about the drum to produce the required friction.

When not in service the standard is allowed to descend into the post sufficiently 25 to permit the pavement opening m to be closed by the cover M^1 . When the apparatus is to be used, the cover is removed, the standard elevated to the required height above the pavement by means of the rack 30 B^2 , rack wheel C^1 , and connected gearing; when thus extended it may be held by the pawl D^6 , or more reliably when fully elevated, by the insertion of the pin A^3 beneath the lower end of the standard. The hoisting 35 gear is then operated to raise or lower the ash-cans or other loads from the cellar to the pavement or waiting cart, in the obvious manner. A reversal of the operation returns the apparatus to the space beneath the 40 pavement. The core B^1 is of T-section and fits snugly within the standard B . A rivet B^6 extends through the standard and a cylindrical boss B^6 forming the lower end of the core and holds the rack in place. A 45 notch b^1 formed in the boss receives the pin A^3 and engages it reliably. The engagement of the leg F^1 in the sleeve B^4 permits the hoisting gear to be faced in any direction, and the only alterations generally required in adapting the apparatus for service 50 as a cellar ash-hoist, are in the length or height of the post and standard to conform to the height of the cellar; the elevating mechanism and hoisting gear remaining the 55 same in nearly all cases.

The apparatus occupies but little space and is easily and quickly conditioned for service. The construction shown permits it to be easily and economically manufactured.

60 I claim:—

1. In a hoisting apparatus, a fixed tubu-

lar post, a tubular standard inclosed in said post and constructed to be raised or lowered telescopically therein, a rack in said standard, means for securing the rack to the 65 standard, a train of gearing carried by said post and constructed to move said standard by engagement with said rack, said standard having a slot in front of the rack through which said train of gearing projects to engage the rack and means on the support of 70 said train of gearing for engagement with one of said gears for preventing descent of the standard.

2. In a hoisting apparatus, a fixed tubular 75 post, a vertically-slotted tubular standard inclosed by said post and constructed to be raised or lowered therein, a rack inclosed in said standard with its teeth presented to such slot, a train of gearing carried by said 80 post and constructed to engage said rack, a coupling at the upper end of said standard, a sleeve secured in said coupling, a frame, a downwardly projecting leg on said frame received in said sleeve, a plate engaged with 85 the lower end of said sleeve, a screw extending through said plate and into said leg, and a winding-spool and operating mechanism therefor carried on said frame.

3. In a hoisting apparatus, a fixed tubular 90 post, a tubular standard inclosed in said post and carrying a rack, a train of gearing carried by said post and projecting through a slot in said standard to engage said rack, means on the support of said train of gearing for engagement with one of said gears 95 for preventing descent of the standard, and means on the upper end of said standard for raising and lowering a load.

4. In a hoisting apparatus, a fixed tubular 100 post having oppositely located holes in the upper portion thereof, a vertically-slotted tubular standard inclosed in said post and constructed to be raised or lowered therein, a rack inclosed in said standard with its 105 teeth presented to such slot and having a notch in its lower end, a train of gearing carried by said post and constructed to move said standard by engagement with said rack, a pin adapted to be thrust through said 110 holes in said post and through said notch to support said standard, and means on the upper end of said standard for raising or lowering a load.

In testimony that I claim the invention 115 above set forth I affix my signature, in presence of two witnesses.

LOUIS O. FORMAN.
